[57] CLAIM

The ornamental design of an combined electrical plug and circuit breaker, as shown and described.

DESCRIPTION

FIG. 1 is a perspective view, taken from the front, right hand side of an combined electrical plug and circuit breaker showing my new design;

FIG. 2 is a top plan view thereof;

FIG. 3 is a bottom plan view thereof;

FIG. 4 is a view of the right side thereof, the left side being a mirror image;

FIG. 5 is a front view thereof; and,

FIG. 6 is a rear view thereof.

FIG. 1

FIG. 2

FIG. 3

FIG. 4

FIG. 6

FIG. 5
